CLAIM

The ornamental design for a combined hair coloring
application bottle and timer, as shown and described.

DESCRIPTION

FIG. 1 is a perspective view of a combined hair coloring
application bottle and timer showing my new design;

FIG. 2 is a front elevational view thereof, the undis-
closed rear is a mirror image of the front shown;

FIG. 3 is a top plan view thereof; and

FIG. 4 is a bottom plan view thereof.

FIG. 1-FIG. 2-FIG. 3-FIG. 4-
